UNITED STATES PATENT OFFICE.

SOLMAN USIEVICH, OF SAN FRANCISCO, CALIFORNIA, ASSIGNOR TO THE SENG COMPANY, OF CHICAGO, ILLINOIS, A CORPORATION OF ILLINOIS.

BED-DAVENPORT.

1,260,600.

Specification of Letters Patent. Patented Mar. 26, 1918.

Application filed January 26, 1915. Serial No. 4,465.

To all whom it may concern:

Be it known that I, SOLMAN USIEVICH, a subject of the Czar of Russia, residing at San Francisco, in the county of San Francisco and State of California, have invented new and useful Improvements in Bed-Dav- enports, of which the following is a specifica- tion.

This invention relates to improvements in 10 davenport-beds, and more particularly to that class thereof wherein the bed or mat- tress-support is composed of two foldable sections disposed lengthwise the davenport- frame, said sections, together with the bed- 15 ding being adapted to fold within the davenport-frame and below the seat and to be unfolded to form a bed in front of said frame.

Among the objects of the invention are to 20 provide a bed of this character wherein the greatest length of the bed is at a right angle to the davenport-frame, so that the occupant of the bed will be able to repose with his head toward the back of the davenport; to 25 provide a comparatively simple and inex- pensive mechanism for supporting in a sta- ble manner and operating the moving parts; and to so arrange the same when one bed- 30 section is unfolded that it and its com- panion are substantially balanced upon a com- mon center, thereby reducing the labor in- 35 volved both in opening and closing the bed.

Other objects and advantages of the in- 40 vention will hereinafter appear, and the novel features thereof will be particularly 45 pointed out in the appended claims.

Referring to the drawings:

Figure 1 is a view partly in elevation and 40 partly in section of a davenport embodying my invention, the bed being shown folded and out of use within the davenport-frame;

Fig. 2 is a similar view, the bed being 45 illustrated as partly opened;

Fig. 3 is a fragmentary view in perspec- 50 tive hereinafter referred to;

Fig. 4 is a view similar to Figs. 1 and 2, the bed being illustrated as unfolded and 55 in operative position;

Fig. 5 is a horizontal sectional view 50 through the davenport frame above the open bed, the parts being shown in the same position as in Fig. 4 and broken away to save space; and

Fig. 6 is a detail enlarged illustrating a 55 joint hereinafter described.

Similar numerals of reference indicate similar parts in all the figures of the drawings.

I employ the conventional form of daven- 60 port-frame, and, as illustrated, the same con- sists of the opposite ends 3, 3, connected by the back-wall 1, and front cross-bar 5 which may have inward extensions 5^a forming op- 65 posite stops. The upper edge of the back- wall may be surmounted by the usual mold- 65 ing 6, and the ends by the arms 4.

The upholstered back 8, may be movably 70 connected to the davenport-frame in any de- sired manner, but is preferably movably con- 75 nected at its upper edge to the opposite ends 3 by means of pivots 7, the back-wall being formed with a shallow recess 2, for the pur- 80 pose of receiving the back when occupying its retracted position, all as clearly shown in Figs. 2 and 4. For the purpose of auto- 85 matically retracting the back, when the same is released from the seat, in a manner here- 90 inafter explained, one or more retracting- 95 springs 10 may be connected to the back and be seated in sockets formed in the back- wall.

The seat 14, is provided on its upper side 95 with the usual upholstery 15, and each of its front corners has secured thereto, as at 18, depending rigid standards 16, prefer- 100 ably angular in cross-section. Pivoted as at 19 to the opposite ends of the seat and near its rear edge, are legs 21, the same being disposed oppositely to the standards 16. These legs are extended above their pivots 105 19 forming extensions 20, and the latter are at their extremities pivoted as at 23, to short standards 24, bolted to the opposite sides and at intermediate points of the foot-sec- 110 tion 25 of the folding-bed or mattress-sup- port.

This section 25 of the bed-frame exceeds 100 in width the sofa-seat, the rear edge of the former projecting a considerable distance back of the seat and substantially agreeing 105 with the depth of the davenport frame. The front edge of the section 25, however, ter- minates short of the front edge of the seat, when the bed and seat are in their unfolded positions (see Fig. 4) but coincides with it 110 when the bed and seat are folded (see Fig. 1).

A short spacing-section 17, has its sides pivoted, as at 16^a, near their middles, to the lower ends of the rigid standards 16, and at 110

their ends, pivoted, as at 27, to the ends of the side-bars of the foot-section 25.

Below the latter section, and corresponding in proportions thereto, is the main or 5 head-section 30. The side-bars of this section are pivoted, as at 29, to the lower ends of the spacing-section 17, immediately above and in rear of the cross-piece or bar 5, of the sofa-frame, and at their rear ends, said 10 bars are pivoted, as at 44, to the corresponding ends of a pair of rigid supporting-links 43, the front ends of the latter being pivoted to the ends 3, near their bases. Swinging upward and forward on the pivots 42, it 15 will be seen the head-section 30 of the bed will be raised, and, of course, a reverse movement of the links will have the effect of lowering the section to the position in which it is shown in Figs. 1 and 2.

20 Pivoted upon a rod 32, near each of the ends 3, at their front edges and immediately above the cross-bar 5 and the pivots 29 between the head-section 30 and the spacing section 16, are triangular-shaped double 25 bell-crank levers 36. Each of the double bell-crank levers 36, has its rear branch 34, pivoted at 35, to one of the side-bars of the head-section 30, at an intermediate point of said side-bar, and its forward branch pivot- 30 ed, as at 37, to the rear end of the rear section 38, of a jointed link 39, the front section 41, of the link, being pivoted to the bolt 27, serving as a pivoting means between the foot-section 25 and the spacing-section 35 17. The joint between the link-sections 38 and 41, is formed by the pivot 40, so that said jointed link is capable of folding (as in Fig. 1) and extending (as in Figs. 2 and 4).

40 Upon each of the bolts 27, which, as before stated, serve as means for pivoting the side-bars of the foot-section 25 with the ends of the spacing-section 17, there may be coiled a spring 45, the terminals of which extend at opposite sides of the coil and bear upon the horizontal flanges of both the side-bars of the section 25 and the spacing-section 17, the tendency of the springs being to maintain these sections in horizontal alinement. When, therefore, these parts are folded so as to be disposed at an angle to each other, such positioning is resisted by the springs, so that the latter are thereby placed under tension.

55 Taking the parts as shown in Fig. 1, wherein the davenport is illustrated in its closed position with the front end of the head-section resting upon the stops 5^a, it will be seen that by reason of the link connection between the seat and the foot-section 25, the former is lowered upon and supported by the spacing-section 17, (which assumes a vertical position,) and at its rear end by a transverse sill or ledge 49, secured 60 to the back-wall of the davenport frame.

The lower or head-section 30 of the bed is positioned in a plane below and substantially parallel with the foot-section 25, the intervening space being occupied by the mattress and bed-clothes (not shown).

70 When it is desired to use the davenport as a bed, the spring-catch 11 is disconnected between the seat and movable back 8, the spring 10 acting to draw the back rearwardly, as heretofore explained after which 75 the seat is automatically raised or thrown upwardly by the springs 45 to a position somewhere between the positions shown in Figs. 1 and 2. The seat may be readily 80 grasped when thus raised and manually and successively moved to the positions shown in Figs. 2 and 4. It will be observed that upon elevating the seat the foot-section 25 of the bed automatically separates from the seat (see Fig. 2), the legs assuming a position at 85 a right-angle to the frame so as to support the same when lowered to operative position, as shown in Fig. 4. As the seat and foot-sections continue their lowering movement (from the position shown in Fig. 2 to that 90 shown in Fig. 4), the links 38 and 39 serve to swing the triangular shaped bell-crank forwardly upon rod 32, said bell-crank, in turn, lifting the head-section 30 and causing 95 it to assume a horizontal position in the same plane as the foot and spacing sections, so that a continuous bed-frame is produced. When thus elevated, the head-section 30 will be supported at or about its middle by the bell-crank and at its rear end by the two 100 supporting-links 43. It will be noted that the rocking of the bell-crank upon their pivots 32, not only elevates the head-section 30, but also projects it and the foot-section 105 forwardly, so that the latter section and the spacing-section lie in advance of the davenport-frame, as shown in Fig. 4.

110 It will be understood, of course, that any desired construction of mattress-supporting wire fabric may be employed, such forming no part of my invention. In the present instance I have shown the sides and ends of the fabric connected to the frame-bars of the bed-frame by means of coiled springs 31, but these may be omitted and the fabric connect- 115 ed directly to such bars.

120 In operation, after the seat has been released from its locking engagement with the back and has been slightly elevated by the expansion of the springs 45, the back edge of the seat is grasped by the operator, in the manner heretofore described, and elevated to the position in which it is shown in Fig. 2. This movement of the seat permits the foot-section to separate from it, the legs automatically assuming an angular 125 position with relation to the seat and foot-section and the links 38 and 39 alining with each other and being therefore in position to elevate the inner or head-section. Thus far 130

the latter section has not been affected by the opening of the seat and foot-section. When, however, the links 38 and 39 aline, further movement of the seat and the foot-section causes said links to elevate or rock the triangular rocking bell-crank levers 33 from the position in which they are shown in Figs. 1 and 2, to the position in which they appear in Figs. 4 and 5. During this 10 operation it will be apparent that the weight of the seat and the foot-section act to counterbalance the head-section and hence aid in the operation of raising the same, such being by reason of the fact that when the 15 seat and foot-section have been elevated approximately to the position in which they are shown in Fig. 2, these parts are in front or at the opposite sides of the pivots 32 of the bell-cranks. So it is also in the operation 20 of closing the bed. In this latter operation, the operator grasps the outer end of the foot-section and elevates it, when the head-section begins to lower and the bell-cranks swing or rock to the rear, the combined weight of the two serving to counterbalance the weight of the seat and foot-sections to some extent. Thus it will be seen that the bed may be operated with very slight manual exertion. When the bed is 25 folded or closed the rear edge of the foot-section rests upon the sill 49, and by reason of the link-connection between the foot-section and the seat, the latter collapses upon the former and is supported thereby. In 30 thus collapsing, it will be seen that the supporting-leg 21 assumes a position parallel to the foot-section, so that both it and the foot-section extend rearwardly under and lie partly back of the back of the davenport 35 when the latter has been drawn out against the tendency of the springs 10 so that its lower edge may again engage with the catch 11.

The bell-crank levers may be given shapes 40 other than as shown, the only essential being that substantially the pivotal relations shown be preserved.

Having described my invention, what I claim is:

- 50 1. In a davenport-bed, the combination with a main-frame, of a multiple sectional bed-frame, comprising two sections, foldable one over the other, and one of which is lowerable in the main-frame, a spacing-section connecting said two sections at their adjacent ends, opposite triangular bell-crank levers fulcrumed at one of their angles in the main-frame, pivotal connections between said levers at one of their angles and said lowerable section, and a link-connection 55 between each of the remaining angles of the bell-crank levers and the pivot point between the uppermost section and the spacing-section.
- 60 2. In a davenport-bed, the combination 65 with a main-frame, of a multiple sectional bed-frame, comprising two sections, foldable one over the other, and one of which is lowerable in the main-frame, a spacing-section connecting said two sections at their adjacent ends, opposite triangular bell-crank levers fulcrumed at one of their angles in the main-frame, pivotal connections between one 125 of the angles of said levers and said lowerable section, and a folding link-connection between each of the remaining angles at points above the horizontal plane of the bed-frame and one of the remaining sections. 130

with a main-frame, of a multiple sectional bed-frame, comprising two sections, foldable one over the other, and one of which is lowerable in the main-frame, a spacing-section connecting said two sections at their adjacent ends, opposite triangular bell-crank levers fulcrumed at one of their angles in the main-frame, pivotal connections between said levers at one of their angles and said lowerable section, a link-connection 70 between each of the remaining angles of the bell-cranks and the pivot point between the uppermost section and the spacing-section, and a pair of rigid supporting-links pivoted at their lower ends in the main-frame and at 75 their upper ends to the lowermost section.

3. In a davenport-bed, the combination with a main-frame, of a multiple sectional bed frame, comprising two sections, foldable one over the other, and one of which 80 is lowerable in the main-frame, a spacing-section connecting said two sections at their adjacent ends, opposite triangular bell-crank levers fulcrumed at one of their angles in the main-frame, pivotal connections 85 between said levers at one of their angles and said lowerable section, a pair of folding links between each of the remaining angles of the bell-cranks and the pivot point between the uppermost section and the spacing-section, and means for supporting the 90 rear end of the lowermost section.

4. In a davenport-bed, the combination with a main-frame, of a multiple sectional bed-frame, comprising two sections, foldable one over the other, and one of which is lowerable in the main-frame, a spacing-section connecting said two sections at their adjacent ends, opposite triangular bell-crank levers fulcrumed at one of their angles in the main-frame, pivotal connections between said levers at one of their angles and said lowerable section, a pair of folding links between each of the remaining angles of the bell-cranks and the pivot points 100 between the uppermost section and the spacing-section, and rigid links pivoted at their lower ends to the main-frame and at their upper ends to the rear end of the lowermost section. 105

5. In a davenport-bed, the combination with a main-frame, of a multiple sectional bed-frame, comprising two sections, foldable one over the other, and one of which is lowerable in the main-frame, a spacing-section connecting said two sections at their adjacent ends, opposite triangular bell-crank levers fulcrumed at one of their angles in the main-frame, pivotal connections between one 120 of the angles of said levers and said lowerable section, and a folding link-connection between each of the remaining angles at points above the horizontal plane of the bed-frame and one of the remaining sections. 125

6. In a davenport-bed, the combination with a main-frame, of a foldable bed comprising a main, a foot, and an intermediate spacing section connected together, mechanism located in the main-frame for guiding and supporting the bed in both its folded and unfolded positions, a seat, supports between the same and the spacing-section, and legs pivotally connected to the opposite ends 5 of the seat and extending beyond the latter, and pivoted to the adjacent foot-section and serving when extended to directly support the said foot section.

7. In a davenport, the combination with 10 a main-frame, a foldable bed-frame formed in three pivotally connected sections, opposite triple-arm bell-crank levers pivoted at the ends of one of their arms to the main-frame, at another of their arms loosely connected to the bottom-section, and opposite pairs of freely foldable links loosely connected to the remaining arms of the bell-crank and to the middle section, whereby 15 said middle section when being unfolded 20 serves through said pairs of links when in alignment as a lever for drawing the bell-crank forward and thereby raising the said bottom section of the bed-frame.

8. A davenport-bed, comprising, a main-frame, a bed-frame composed of articulated sections connected with the main-frame and foldable therein, opposite three-arm bell-crank levers, each having one of its arms pivoted in the main-frame and another of 25 its arms pivotally connected with the rear-most section of the bed, links connecting the remaining arms of the bell-crank levers and the pivotal connections between those sections beyond the innermost section, and supports for the outer end of the bed when unfolded. 30

9. A davenport-bed, comprising a main-frame, fulcrums at the opposite ends thereof, a bed-frame composed of sections articulated by rule-joints connected with the main-frame and foldable therein, opposite three-arm bell-crank levers, each having one of its arms pivoted in the main-frame and having another of its arms pivotally connected with 35 the rear-most section of the bed-frame, links connecting the remaining arms of the bell-crank levers with the pivotal connection between the two sections of the bed immediately in advance of the rear-most section, 40 and supporting-links pivoted at their lower 45

ends within the main-frame and at their upper ends to the opposite sides of the rear-most bed-section, whereby after the bed is sufficiently unfolded for the two sections immediately in advance of the rear-most section 60 to come into alignment they are maintained in alignment by the rule-joints and rest upon the fulcrums and thereby serve as a lever for elevating the rear-most section and swing the bell-crank and supporting-links to their upper or supporting position. 65

10. A davenport-bed, comprising a main-frame, fulcrums at the opposite ends thereof, a bed-frame composed of sections articulated by rule-joints connected with the main-frame and foldable therein, opposite three-arm bell-crank levers, each having one of its arms pivoted in the main-frame and having another of its arms pivotally connected with the rear-most section of the bed-frame, 70 links connecting the remaining arms of the bell-crank levers with the bed in advance of the rear-most section, and movable supports within the main-frame and connected to the rear-most section of the bed-frame, whereby 75 after the bed is sufficiently unfolded for the two sections immediately in advance of the rear-most section to come into alignment they are maintained in alignment by the rule-joints and rest upon the fulcrums and thereby 80 serve as a lever for elevating the rear-most section and swing the bell-crank and movable supports to their upper or supporting position. 85

11. In a davenport-bed, the combination with a main-frame, of a multiple sectional bed-frame, three-arm bell-crank levers at the opposite ends of the main-frame and each pivoted at one of its arms therein and at another of its arms to the rear-most section and having its remaining arm disposed above the plane of the folding bed when the latter is unfolded, and link connections between the third arm and a portion of the folding bed in advance of the rear-most section, 90 whereby said bell-crank levers form supports for the intermediate portion of the bed. 95 100

In testimony whereof I have hereunto set my hand in the presence of two subscribing witnesses.

SOLMAN USIEVICH.
